PULL

Bruce N. Bingham, Rockford, Ill., assignor to Amerock Corporation, Rockford, Ill.

Filed Dec. 3, 1971, Ser. No. 204,795

Term of patent 14 years

Int. Cl. D8—06

U.S. Cl. D8—173

FIG. 1 is a front view of a pull incorporating my new design.

FIG. 2 is a side view as seen from the right of FIG. 1.

FIG. 3 is a bottom view of the pull.

FIG. 4 is an enlarged sectional view taken along the line 4—4 in FIG. 1.

FIG. 5 is an enlarged sectional view taken along the line 5—5 in FIG. 1.

I claim:

The ornamental design for a pull, as shown.
